UNITED STATES PATENT OFFICE.

JOHN OTIS PHILLIPS, OF NEW YORK, N. Y.

ELECTRIC-LAMP SOCKET.

SPECIFICATION forming part of Letters Patent No. 439,304, dated October 28, 1890.

Application filed February 5, 1890. Serial No. 339,246. (No model.)

To all whom it may concern:

Be it known that I, JOHN OTIS PHILLIPS, of the city and county of New York, in the State of New York, have invented a certain new and useful Improvement in Electric-Lamp Sockets, of which the following is a specification.

My improvement relates to "electric-lamp sockets," so called, and more particularly to that class of such sockets called "pendent sockets."

I will describe in detail my improvement, and then point out the novel features in claims.

In the accompanying drawings, Figure 1 is a side elevation of a lamp-socket embodying my improvement, showing a lamp secured thereto. Fig. 2 is an end view of a lamp detached. Fig. 3 is an end view of the main or body portion of the socket at that end thereof to which the lamp is attached. Fig. 4 is a similar view, but showing a certain switch in a different position from that shown in Fig. 3. Fig. 5 is an end view of a certain head employed on the socket, which head receives the main-circuit wires. Fig. 6 is a similar view showing the parts in a somewhat different position from that shown in Fig. 5. Fig. 7 is a vertical section of the main or body portion of the socket, the said head being removed. Fig. 8 is a view showing a modification. Fig. 9 is a longitudinal central section through the socket, showing the several parts in assembled adjustment.

Similar letters of reference designate corresponding parts in all the figures.

A designates an electric-lamp globe, which may be of the usual or any desired construction.

a designates the filament thereof. The lamp-socket is secured in a head A', here shown as a metallic ring. It is thus secured by plaster-of-paris or other suitable means. Circuit-wires extend from the filament through said head and connect near their outer ends with contact-pieces a', which are secured upon the outer ends of the head. Extending from the sides of the head and, as shown, opposite each other are pins or projections a'.

C designates the main or body portion of the lamp-socket. As shown in the example of my improvement illustrated in Figs. 1, 3,

4, and 7, said main or body portion is cylindrical. It may be made of any suitable non-conducting material. Extending lengthwise 55 through it and about centrally is a passage c. Secured upon said head near one end is a metallic ring c', which metallic ring extends for a considerable distance beyond the end of the main or body portion C, so that an internal 60 socket c² is formed inside said ring and outside of the main or body portion C, and when the point where the said ring c' is secured to the main or body portion C the ring is provided with a circumferentially-extending rib c³. Arranged upon the exterior of the ring c' and surrounding the same is a ring c⁴, provided 65 near its inner edge with a rib c⁵, which extends over and embraces the rib c³ of the ring c'. The ring c⁴ is thus retained upon the ring c'; but it may rotate about the same.

In Fig. 1 I have shown more clearly that the ring c⁴ is provided with a slot c⁶ upon its inner edge, into which slot extends a pin c⁷ from the ring c'. This pin and slot operate as stops to limit the degree of rotation which may be imparted to the ring c⁴. The ring c⁴ is provided with "bayonet-slots" c⁸, opening upon the outer edge of said ring, and which are, as shown, opposite each other. In 80 the ring c' are formed slots c⁹, which are straight and open at their outer ends upon the edge of the ring c'. When the globe A is to be secured to the lamp-socket, the head A' thereof is passed into the socket c², the pins or projections a² thereon passing inwardly through the slots c⁹ in the ring c', and also through longitudinally-extending portions of the slots c⁸ in the ring c⁴. Of course the ring c⁴ has been previously rotated into such a position as to admit of this. When the pins or projections have reached the bottoms of the slots c⁸, the rings c⁴ are rotated so as to form bayonet-locks between the head of the lamp-globe and the lamp-socket, as shown more 85 clearly in Fig. 1. Upon the other end of the lamp-socket is secured a head D. This head is made of any suitable non-conducting material, and is provided centrally with an aperture through which may extend main-circuit 90 wires d in the ordinary manner. The inner end of said head, or that shown more clearly in Figs. 5 and 6, is provided with binding-screws d', which binding-screws also consti-

tute circuit-closers. The circuit-wires d are secured by said binding-screws. Upon the head D is secured a metallic ring D', and surrounding the metallic ring D' is another metallic ring D². The metallic ring D' is provided with a rib near one of its edges and the metallic ring D² with a corresponding rib d³, which embraces the rib on the ring D'. The ring D² may thus rotate upon the ring D', but is secured thereon. A stop similar to that previously described is provided to prevent a too extended rotary movement being imparted to the ring D². Upon the main or body portion C of the lamp-socket and extending from the sides thereof and opposite each other, as shown, are pins or projections d⁴.

Upon the end of the main or body portion C, to which the lamp A is secured, are two contact-pieces e e' and upon the end of said main or body portion, to which the head D is secured, are two other contact-pieces f f'. The contact-piece e is electrically connected to the contact-piece f by a wire f², extending through the main or body portion C. The contact-piece e' is provided with a tongue-shaped circuit-closer f³, which extends into the passage c and, as shown, nearly through one end of the main or body portion C to the other. This circuit-closer is resilient, and is adapted to be forced against the contact-piece f', in order to close circuit on the lamp. I have shown a switch for closing said circuit, which comprises a shaft G, which is journaled in the main or body portion C, and is provided upon the exterior of the main or body portion with a hand-piece g, by which the shaft may be rotated. Upon the shaft is a metallic rectangularly-shaped block H, which is rigidly secured upon said shaft and rotates with it. Such block is oblong. When the shaft is so rotated that one of its long sides is next the circuit-closer f³, the circuit-closer is allowed to spring away from the contact-piece f', in order to break circuit; but when one of the ends of the block H is brought into contact with the circuit-closer f³ it forces said circuit-closer into contact with the contact-piece f' to close circuit. It will be observed that the hand-piece g may be moved in either direction, either to close or open circuit, as

desired, and that, owing to flat surfaces upon the block H being always presented to the circuit-closer, accidental rotation of the shaft is prevented.

In Fig. 8 I have shown a modification of 55 the means for securing the lamp to the socket. Such a modification consists, merely, in an inversion, by which, instead of the head A' of the lamp extending into a socket formed by the ring c' upon the main or body portion C, 60 the rings c' and c⁴ would be arranged upon the lamp-head A', and would receive the end of the main or body portion C within them in manner similar to the means for securing the head D upon the main or body portion C. In 65 such case of course the pins a² would be upon the main or body portion, and the slots c⁸ c⁹ would be upon the lamp-head A'.

What I claim as my invention, and desire to secure by Letters Patent, is—

1. The combination, with two separable parts of an electric-lamp socket, of a lock comprising a stationary ring secured to one of the separable parts and provided with a slot, a movable ring provided with an angular slot, 75 a pin secured to the other of the separable parts and adapted to enter both the slots in the said rings, whereby the separable parts may be locked without rotation relatively to each other, substantially as set forth. 80

2. The combination, with two separable parts of an electric-lamp socket, of a lock comprising a stationary ring having a vertical slot and a pin, the said stationary ring and pin being secured to one of the separable parts, a 85 movable ring provided with a horizontal slot to receive said pin and with an angular slot, and a pin on the other of the two separable parts adapted to enter both said vertical and angular slots, whereby the separable parts 90 may be locked without rotating the one relatively to the other and the movable ring limited in its movement, substantially as set forth.

JOHN OTIS PHILLIPS.
